IGNITER FOR GAS BURNERS

Tony G. Failla, Detroit, Mich.

Application February 4, 1935, Serial No. 4,909

1 Claim. (Cl. 175—91)

This invention relates to igniters for gas burners and has for the primary object the provision of an electrical device operable from an electric house circuit and provides a safe, efficient and economical device which may be easily operated to ignite fuel of a burner and thereby eliminate the use of matches and the like.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a side elevation illustrating an igniter constructed in accordance with my invention.

Figure 2 is a top plan view illustrating the same.

Figure 3 is a vertical sectional view illustrating the device.

Figure 4 is a horizontal sectional view illustrating the device.

Figure 5 is a sectional view illustrating a handle supporting an electrode of the device.

Figure 6 is a diagrammatical view illustrating the wiring diagram of the device.

Referring in detail to the drawings, the numeral 1 indicates a casing mounted adjacent a burner 2. A partition 3 is located in the casing for dividing the latter into compartments, one of which receives an electrical transformer 4 and the other receives an electrical coil 5 of the vibrator type. An electric circuit is employed between the coil 5, the transformer 4, and the burner 2 and has interposed therein spaced contacts 6 supported respectively by the partition 3 and the coil 5. The transformer 4 is connected to an electrical extension cord 7 having the usual plug 8 whereby the device may be connected into an electric house circuit, shown in Figure 2.

An igniter element 9 is electrically connected to the coil 5 by a conductor 10. The element 9 consists of an elongated cylindrical handle 11 constructed of a suitable insulating material and is provided with a bore. Mounted in the bore and projecting beyond one end of the handle is an electrode 12. A chamber 13 is formed in the handle 11 and communicative with the bore to receive one end of the electrode which is shaped to form a terminal 14 detachably secured to the conductor 10. A removable cap cover 15 closes

the chamber 13 and is apertured to receive the conductor 10.

A circuit maker and breaker 16 is slidably supported by the casing and consists of a stem 17 mounted for vertical movement with respect to the casing and carries at its lower end a contact head 18 adapted to bridge the contacts 6 when in its lowermost position. A rack 19 is secured to the upper end of the stem and has forked end portions to receive the igniter element, the weight of which lowers the stem 17 to disengage the contact 18 from the contacts 6 and thereby break the circuit between the transformer and the coil, rendering the igniter element inoperative. A coil spring 20 is mounted on the stem between the rack 19 and the casing acting to urge the stem 17 upwardly to engage the contact 18 with the contacts 6 for completing the circuit between the transformer and the coil when the igniter element is removed from the 20 rack.

To ignite fuel from the burner 2 the igniter element is removed from the rack and the electrode 12 brought into engagement with the burner causing a spark which ignites the fuel. The replacement of the igniter element on the rack renders the device inoperative.

Having described the invention, I claim:

A device for the purpose indicated comprising a casing having an interior division wall to divide it into compartments, a transformer disposed in one compartment, a spark coil disposed in the other compartment, the partition being terminated short of one wall of the casing and the spark coil having a contact overlapping the edge of the partition, a second contact carried by the partition in the same plane as the coil carried contact but spaced therefrom, an igniter element having a flexible conductor connecting it with the spark coil, and a combined igniter element rest and circuit maker and breaker comprising a rack for receiving the igniter element when not in use, a stem having a sliding mounting in the top wall of the casing, a contact carried at the lower end of the stem, and a compression spring surrounding the stem and bearing against the rack to elevate the latter and bring the stem carried contact into engagement with the first said contacts, the igniter element having a sufficient weight when mounted on the rack to depress the latter and disengage the stem carried contact from the other contacts.

TONY G. FAILLA.
